UNITED STATES PATENT OFFICE.

HAROLD E. YARROW, OF GLASGOW, SCOTLAND.

WATER-COOLED VALVE FOR CLOSING THE FUNNELS OF SUBMARINE VESSELS.

1,337,110.

Specification of Letters Patent. Patented Apr. 13, 1920.

Application filed October 30, 1917. Serial No. 129,310.

To all whom it may concern:

Be it known that I, HAROLD EDGAR YARROW, a subject of the King of Great Britain, residing in Glasgow, Scotland, have invented a certain new and useful Water-Cooled Valve for Closing the Funnel of Submarine Vessels, of which the following is a specification.

The invention relates to means for closing the aperture of a funnel of a submarine vessel to prevent access of water when the vessel is submerged.

According to the invention, the aperture is closed by a slide valve, which is water cooled both in the open and closed positions by the circulation of water, which enters the valve chest by one orifice and leaves by another.

In the accompanying drawing, Figure 1 is an elevation, partly in section, and Fig. 2 a plan, partly in section, of a valve according to the invention.

A_1 is the upper and A_2 is the lower part of the funnel. B is the valve closing in the position shown, the aperture between the parts A_1 and A_2 . C is the valve chest secured to the parts A_1 and A_2 . D is a screwed spindle actuating the valve B by means of the hand wheel E . F is a cover to the valve chest C , through which the spindle D passes. G_1 , G_2 , G_3 are guides for the valve B . I_1 , I_2 are the valve seatings.

In the open and closed positions of the valve water is admitted at the orifice H in the valve cover F or by an orifice H_1 , shown in dotted lines, in the valve chest C , and escapes by the orifice K in the valve chest C , after traversing the passage J , so that the valve is kept cool and distortion prevented, whether the valve is open or shut.

I am aware that it is known to cool sliding dampers for flues by the circulation of water and do not broadly claim the use of water for this purpose.

Having thus described the nature of the 45 said invention and the best means I know of carrying the same into practical effect, I claim:

1. In combination with the funnel of a submarine vessel of a water cooled solid 50 valve of rectangular cross section, said valve having an aperture adapted when the valve is in the open position to register with the aperture in the funnel, and a valve casing surrounding the funnel having annular seatings for the valve and an inlet and an outlet for sea water.

2. In combination with the funnel of a submarine vessel, a water cooled solid valve of rectangular cross section, said valve having an aperture adapted, when the valve is in the open position, to register with the aperture in the funnel, a valve casing surrounding the funnel, said valve casing having annular seatings, and an inlet and an 65 outlet for sea water, a cover secured to said casing at one end thereof and having a stuffing box, and a solid valve stem passing water-tight through the stuffing box.

3. In combination with the funnel of a 70 submarine vessel, of a water cooled solid valve of rectangular cross section having an aperture adapted, when the valve is in the open position, to register with the aperture in the funnel, a valve casing surrounding 75 the funnel and having annular seatings, and an inlet and an outlet to permit the passage of sea water to and from said casing, said casing being further provided with guides for the valve.

In testimony whereof I have signed my name to this specification in the presence of two subscribing witnesses.

HAROLD E. YARROW.
